FIG.1

UNITED STATES PATENT OFFICE

2,397,607

CONTROL MECHANISM

William M. Hurst, Douglaston, N. Y., assignor to
 Hazeltine Corporation, Washington, D. C., a
 corporation of Delaware

Application August 1, 1944, Serial No. 547,636

14 Claims. (Cl. 74—10)

This invention is directed to a control mechanism. While being subject to a variety of applications, the invention is especially suited for controlling the variable element of an adjustably tuned circuit and will be described in that connection.

As is well known, adjustably tuned circuits are utilized very generally in communication, electronic, and similar apparatus. Where the apparatus is operated in the ultra-high portion of the frequency spectrum, the adjustably tuned circuit frequently consists of a variable inductor, tuned by a condenser which may be comprised in whole or in part of the inherent capacitance of the inductor and related stray capacitances. In such a case, the operating frequency of the tuned circuit is usually controlled through the adjustment of a tuning core or slug associated with the inductor and effective to determine the apparent inductance thereof in accordance with the degree of coupling therebetween. One form of control mechanism, employed to vary the position of the tuning slug and thereby vary the inductance and operating frequency of the tuned circuit, includes a threaded shaft to one end of which the tuning slug is secured. A control knob affixed to the opposite end of the shaft facilitates accurate tuning adjustments. While such prior art control mechanisms permit the tuned circuit to be adjusted over a given range of operating frequencies, they generally do not include provisions for arresting the control mechanism at pre-selected control positions, as is required to adjust the tuned circuit rapidly and accurately to one or more desired operating frequencies within its range. In some installations, such a feature is highly desirable.

Other control mechanisms enabling a tuned circuit to be adjusted over a given operating frequency range and including provisions for rapidly adjusting the circuit to one or more predetermined frequencies within the range have already been proposed. They are commonly referred to in the art as "push-button tuning devices" and are usually associated with an adjustably tuned circuit in which the variable element is an air-dielectric condenser, including a stator and a co-operating rotor. Such arrangements comprise more or less complicated mechanical structures for controlling the position of the rotor of the variable condenser. In addition to their mechanical complexities, these arrangements represent a substantial mass or weight which may be objectionable in applications where the weight factor is important, as in airborne installations.

It is an object of the present invention, therefore, to provide a control mechanism which is not subject to one or more of the above-mentioned limitations of prior art arrangements.

5 It is another object of the invention to provide an improved control mechanism having a simplified and inexpensive mechanical construction.

It is another object of the invention to provide an improved control mechanism which permits 10 continuous adjustment of a controlled element and includes provisions for quickly and accurately effecting preselected adjustments of the controlled element.

A control mechanism, in accordance with the 15 invention, comprises a rotatable shaft to be coupled to a controlled element for exerting thereon a control effect determined by the rotational displacement of the shaft with respect to a reference position and means for angularly displacing the

20 shaft with respect to its reference position. The control mechanism includes a first stop member, a threaded member having an arcuate configuration, and means for supporting such members for relative rotation therebetween in response to rotation of the rotatable shaft. At least one co-operating stop member is adjustably supported by the threaded member in a preselected position to register with the first stop member and arrest the shaft in a corresponding preselected 25 controlled position. A locking device is provided for the co-operating stop member, having a resilient portion disposed in such relation to the threaded member as yieldably to engage the co-operating stop member in any position of adjustment there-

30 of to permit adjustment of the co-operating stop member to its preselected position by rotation on the threaded member, while locking the co-operating stop member against movement due to relative movement between the first stop member and 35 the threaded member.

For a better understanding of the present invention, together with other and further objects thereof, reference is had to the following description 40 taken in connection with the accompanying drawing, and its scope will be pointed out in the appended claims.

In the drawing, Fig. 1 is an elevational view, 45 partly in cross section, of a control mechanism in accordance with the invention; Fig. 2 is a cross-sectional view taken as indicated by directional arrows 2—2 of Fig. 1; Fig. 3 is an end elevation taken as indicated by directional arrows 3—3 of Fig. 1; while Fig. 4 represents a portion of the Fig. 1 arrangement in modified form.

50 Referring now more particularly to Fig. 1 of the

drawing, there is illustrated a control mechanism embodying the invention utilized for controlling an adjustably tuned circuit. The tuned circuit may constitute a component of a wave-signal translating apparatus, such as a wave-signal receiver, but since the invention may be completely understood from a consideration of the adjustment of the tuned circuit alone, the remainder of the apparatus has been omitted from the drawing.

The tuned circuit is provided by a parallel combination of a variable inductor L and a condenser C, represented in broken-line construction since it may be comprised in whole or in part of the inherent capacitance of the inductor and stray capacitances associated therewith. Inductor L is supported by a cylindrical coil form 10 of a suitable insulating material, as, for example, a thermoplastic resin. A coil-retaining groove 11 in the form of a continuous spiral is milled into coil form 10 and the wall thickness of the coil form is, preferably, as small as practical. The inductor L, per se, consists of a preformed coil having an inner diameter slightly less than the diameter of groove 11. The preformed coil is, preferably, made of a resilient material such as hard drawn brass, silver plated to have an improved conductivity characteristic. The cross section of the coil conductor and the material from which it is formed are selected with reference to the coil diameter so that the free ends 12 and 13 thereof have sufficient self-rigidity to permit direct connection to other circuit components of the equipment. In assembling the described inductor arrangement, the preformed coil is threaded on to coil form 10 with the convolutions thereof received by groove 11. Due to the resiliency of the coil and the relative dimensions of the coil diameter and groove diameter, the coil convolutions firmly engage groove 11 and securely lock the coil in a desired position on form 10.

The described tuned circuit is adjustable over a given range of operating frequencies through a tuning core or slug 14 which is freely movable within coil form 10. Tuning slug 14 may be of either a magnetic or nonmagnetic material, depending upon the variations of inductance required. As is well understood in the art, such a tuning slug is effective to vary the apparent inductance of inductor L in accordance with the coupling therebetween. Where the slug is of magnetic material, the inductance increases with this coupling while the converse effect is obtained through the use of a nonmagnetic material. In the arrangement under consideration, tuning slug 14 is preferably a nonmagnetic silver sleeve. The slug diameter is only slightly less than the inner diameter of coil form 10 so that maximum coupling with inductor L and maximum tuning efficiency result. Slug 14 is suitably secured to one end of a plunger 15, constituting the element controlled by the control mechanism presently to be described.

Tuned circuit L, C is supported by a mounting plate 20 having a right-angle flange portion 21 in which apertures 22 are provided for the purpose of securing the mounting plate to a supporting structure. To this end, coil form 10 is received by a U-shaped bracket 23 and is affixed through a transverse strap 24 thereof to mounting plate 20. Bracket 23 is partially broken away in Fig. 1 to reveal the driving connection to plunger 15.

Considering now the control mechanism of Fig. 1, the illustrated arrangement comprises a rotat-

able shaft 25 to be mechanically coupled to the controlled element, plunger 15, for exerting thereon a control effect determined by the rotational displacement of the shaft with respect to a reference position, identified hereinafter. Shaft 25 is rotatable within and supported by an externally threaded bushing 26. One end of bushing 26 projects through aligned apertures in strap 24 of bracket 23 and mounting plate 20, this end of the bushing being spun over as indicated at 27 to complete an assembly of the mounting plate, bracket and bushing.

A control knob 31 constitutes means for angularly displacing shaft 25 with respect to a reference position. This control knob is locked by 15 way of a set screw 32 to an elongated hub 33, the latter being affixed to one end of shaft 25 through a transverse pin 34 which projects through both the hub and shaft. A cam means 35 secured to the opposite end of shaft 25 is effective mechanically to couple the shaft to plunger 15. The cam is a length of resilient material, such as a section of brass rod, formed to the general configuration of an Archimedean spiral. One end 36 of the formed cam is inserted into an axially disposed socket provided in shaft 25 while the opposite end 37 abuts against the periphery of the shaft. Both such ends of the cam are retained in their described relation with shaft 25 through soldering or welding. In order that the cam may engage plunger 15, a segment of coil form 10 adjacent the cam is cut away, as illustrated in Fig. 1, and the cam is proportioned so as to project therethrough. A coil spring 38 anchored to a vertical projection 39 of bracket 23 is connected with the free end of plunger 15, thereby constituting means for biasing the controlled element into engagement with cam 35. A washer 28 carried by shaft 25 holds the shaft against axial displacement within bushing 26 resulting from the bias of spring 38.

A vertical projection 40 which is struck out of strap 24 of bracket 23 engages certain peripheral portions of the cam to limit the maximum angular displacement of shaft 25 to a predetermined value. One such portion is indicated 41a in Fig. 3, and determines the above-mentioned reference position of shaft 25. The alternate limiting position of the shaft is determined by the engagement of projection 40 with a cam portion indicated 41b. The angular displacement of shaft 25 intermediate the defined limiting positions is approximately 330 degrees for the illustrated arrangement.

The control mechanism also includes a first stop member 50 having a recessed detent portion 51, Fig. 2; a threaded member 52 having an arcuate configuration; and means for supporting these members for relative rotation therebetween in response to rotation of shaft 25. More particularly, stop member 50 is a resilient wiping member mechanically connected with shaft 25 to be angularly driven thereby. This mechanical connection is afforded by the free end of hub 33 which projects through and is spun over an aperture in stop member 50, thereby coaxially supporting this member with reference to shaft 25. Threaded member 52 is preferably circular and is provided with a mounting bracket 53. Threaded member 52 is locked against rotation by being fixedly supported in substantially coaxial alignment with shaft 25. This is accomplished by a mounting collar 63 having an annular shoulder portion which receives mounting bracket 53. The mounting collar 63 is coaxially arranged with

reference to threaded bushing 26 and a lock nut 64, threaded upon bushing 26, clamps bracket 53 to lock threaded member 52 against rotation.

At least one co-operating stop member is adjustably supported by threaded member 52 in a preselected position to register with detent portion 51 of stop member 50 and arrest shaft 25 in a corresponding preselected control position. In its simplest form the co-operating stop device comprises a hexagonal nut 54 threaded on member 52 before the latter is assembled upon its mounting bracket 53. Preferably, a plurality of such co-operating stop members is provided, being individually adjustably supported by member 52 and individually effective in co-operation with stop member 50 to arrest the shaft in one of a corresponding plurality of preselected control positions.

Finally, the control mechanism includes a locking device 55 having a resilient portion disposed in such relation to threaded member 52 as yieldably to engage each cooperating stop member 54 in any position of adjustment thereof, to permit adjustment of the co-operating stop members to their individual preselected positions by rotation on member 52 while locking such stop members against any movement resulting from relative rotation between first stop member 50 and threaded member 52. This locking device is a resilient spider mounted coaxially with and effectively secured to threaded member 52 through collar 63 and lock nut 64. The peripheral portion of the spider has substantially the same configuration as threaded member 52 and is proportioned yieldably to engage each stop member 54.

In considering the operation of the described control mechanism, the function of stop members 50 and 54 will initially be neglected and it will be assumed that control knob 31 is adjusted so that cam portion 41a engages stop projection 40. As indicated above, this condition represents the reference position of shaft 25 in which cam 35 and spring 38 cause tuning slug 14 to be withdrawn from inductor L so as to have substantially zero coupling therewith. For this condition, the inductor exhibits its natural value of inductance and tuned circuit L, C has its minimum operating frequency. As control knob 31 is rotated in a clockwise direction, shaft 25 is angularly displaced in the same sense with respect to its reference position. Such displacement of shaft 25 results in the application of a control effect upon plunger 15 through the agency of cam 35. The magnitude of the control effect is determined by the rotational displacement of the shaft and the configuration of the cam. The controlled element 15 and tuning slug 14 carried thereby are laterally displaced a corresponding amount in the direction of inductor L so as to increase the degree of coupling between the inductor and the tuning slug. The increased coupling results in a decrease in apparent inductance of inductor L and a proportional increase in the operating frequency of tuned circuit L, C. In the limiting condition when shaft 25 has its maximum angular displacement, the degree of coupling between the inductor and its tuning slug is a maximum and the operating frequency of the tuned circuit likewise has its maximum value. Thus, the control mechanism is effective continuously to adjust the operating frequency of the tuned circuit L, C over a given range of operating frequencies. Stop members 50 and 54 permit the operating frequency to be established accurately and rapidly

to predetermined desired frequencies within this range in the following manner.

A particular setting of a given stop member 54 represents a predetermined angular displacement 5 with respect to the reference position of shaft 25. Likewise, a given angular displacement of the shaft represents a given control effect which causes tuning slug 14 to have a predetermined degree of coupling with inductor L resulting in a given operating frequency of the tuned circuit. Therefore, one or more of stop members 54 is manually rotated and adjusted to a preselected position or positions along threaded member 52. This adjustment may be readily accomplished in 15 view of the yielding engagement of lock device 55 with these stop members. Having thus selectively positioned stop members 54, control knob 31 is rotated until the detent portion 51 of stop member 50 registers with a particular stop member 54 and arrests shaft 25 in a corresponding preselected control position to establish a desired operating frequency of the tuned circuit. Since stop member 50 is resilient, any of the co-operating stop members 54 may be passed over to effect 20 registration with a particular one. Thus the shaft 25 may be arrested in a preselected control position corresponding to the adjustment of a particular co-operating stop member 54 irrespective of the previous setting of control knob 31. 25

30 The operator may easily determine the engagement of detent portion 51 of stop member 50 with a co-operating stop member through the changing resistance to turning which results from the wiping action of stop members 50 and 54. Also, 35 locking device 55 locks co-operating stop members 54 in their desired preselected positions against any movement which might otherwise result from this wiping action.

The fragmentary view of Fig. 4 illustrates a 40 modified form of the coupling between the rotatable shaft and the controlled element. This arrangement is generally similar to that of Fig. 1, corresponding components thereof being identified by like reference numerals primed. In the 45 Fig. 4 arrangement, the mounting portion 69 of coil form 10' is offset to have an increased diameter so as to enclose the cam arrangement, presently to be described, which couples shaft 25' with controlled element 15'. This cam arrangement comprises a cylinder 70 having a closed end 71 which is fixed to the free end of shaft 25' for rotation therewith. A cam track 72 is milled into the cam cylinder. This cam cylinder is in coaxial alignment with shaft 25' and controlled element 15', receiving the latter in its open end. 50 The plunger of this embodiment carries a cam-following pin 73 which projects through cam track 72. Pin 73 also engages an internal keyway 74 milled in mounting portion 69 of coil form 10'. A coil spring 75 interposed between the closed end of cam cylinder 70 and the adjacent end of plunger 15' retains pin 73 in engagement with the cam track. Threaded bushing 60' is provided with a retaining collar 16 for receiving coil form 10'. A machine screw 77 locks these elements together. The arrangement of Fig. 4 may be substituted for the corresponding portion of the Fig. 1 arrangement. Where the substitution is made, the operation of the 65 control mechanism will be substantially as described.

If desired, the control mechanism may be modified to include a plurality of rotatable stop members 50 and/or a plurality of threaded members 52 for adjustably supporting additional co-

operating stop members. Such a modification affords greater latitude of preselected control positions for shaft 25.

It will be understood that the control effect exerted upon the controlled element for a given angular displacement of the rotatable shaft may be readily adjusted by the configuration of the cam mechanism.

While the invention has been particularly described in connection with a variable inductor of an adjustably tuned circuit, it will be understood that this is not an exclusive application. For example, the control mechanism may readily be utilized to control a variable condenser or other controlled element.

The control mechanism of the invention will be seen to comprise a relatively few light mechanical elements. Accordingly, it substantially avoids the mechanical complexity of the prior art arrangements mentioned above. Additionally, the control mechanism is quite inexpensive to construct and represents a small mass, rendering it suitable even for airborne installations.

While there have been described what are at present considered to be the preferred embodiments of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A control mechanism comprising, a rotatable shaft to be coupled to a controlled element for exerting thereon a control effect determined by the rotational displacement of said shaft with respect to a reference position, means for angularly displacing said shaft with respect to said reference position, a first stop member, a threaded member having an arcuate configuration, means for supporting said members for relative rotation therebetween in response to rotation of said shaft, at least one co-operating stop member adjustably supported by said threaded member in a preselected position to register with said first stop member and arrest said shaft in a corresponding preselected control position, and a locking device for said co-operating stop member having a resilient portion disposed in such relation to said threaded member as yieldably to engage said co-operating stop member in any position of adjustment thereof to permit adjustment of said co-operating stop member to said preselected position by rotation on said threaded member while locking said co-operating stop member against movement due to relative rotation between said first stop member and said threaded member.

2. A control mechanism comprising, a rotatable shaft to be coupled to a controlled element for exerting thereon a control effect determined by the rotational displacement of said shaft with respect to a reference position, means for angularly displacing said shaft with respect to said reference position, a first stop member, a threaded member having an arcuate configuration, means for mechanically connecting one of said members to said shaft for rotation therewith and for locking the other of said members against rotation to provide relative rotation therebetween in response to rotation of said shaft, at least one co-operating stop member adjustably supported

by said threaded member in a preselected position to register with said first stop member and arrest said shaft in a corresponding preselected control position, and a locking device for said co-operating stop member having a resilient portion disposed in such relation to said threaded member as yieldably to engage said co-operating stop member in any position of adjustment thereof to permit adjustment of said co-operating stop member to said preselected position by rotation on said threaded member while locking said co-operating stop member against movement due to relative rotation between said first stop member and said threaded member.

3. A control mechanism comprising, a rotatable shaft to be coupled to a controlled element for exerting thereon a control effect determined by the rotational displacement of said shaft with respect to a reference position, means for angularly displacing said shaft with respect to said reference position, a first stop member, a threaded member having an arcuate configuration, means for mechanically coupling said first stop member to said shaft to be angularly driven thereby and for locking said threaded member against rotation to provide relative rotation therebetween in response to rotation of said shaft, at least one co-operating stop member adjustably supported by said threaded member in a preselected position to register with said first stop member and arrest said shaft in a corresponding preselected control position, and a locking device for said co-operating stop member having a resilient portion disposed in such relation to said threaded member as yieldably to engage said co-operating stop member in any position of adjustment thereof to permit adjustment of said co-operating stop member to said preselected position by rotation on said threaded member while locking said co-operating stop member against movement due to relative rotation between said first stop member and said threaded member.

4. A control mechanism comprising, a rotatable shaft to be coupled to a controlled element for exerting thereon a control effect determined by the rotational displacement of said shaft with respect to a reference position, means for angularly displacing said shaft with respect to said reference position, a first stop member, a threaded member having an arcuate configuration, means for mechanically supporting said first stop member on said shaft for rotation therewith and for fixedly supporting said threaded member in substantially coaxial alignment with said shaft to provide relative rotation between said members in response to rotation of said shaft, at least one co-operating stop member adjustably supported by said threaded member in a preselected position to register with said first stop member and arrest said shaft in a corresponding preselected control position, and a locking device for said co-operating stop member having a resilient portion disposed in such relation to said threaded member as yieldably to engage said co-operating stop member in any position of adjustment thereof to permit adjustment of said co-operating stop member to said preselected position by rotation on said threaded member while locking said co-operating stop member against movement due to relative rotation between said first stop member and said threaded member.

5. A control mechanism comprising, a rotatable shaft to be coupled to a controlled element for exerting thereon a control effect determined by the rotational displacement of said shaft with

respect to a reference position, a first stop member, a substantially circular threaded member, means for supporting said members for relative rotation therebetween in response to rotation of said shaft, at least one co-operating stop member adjustably supported by said threaded member in a preselected position to register with said first stop member and arrest said shaft in a corresponding preselected control position, and a locking device for said co-operating stop member having a resilient portion disposed in such relation to said threaded member as yieldably to engage said co-operating stop member in any position of adjustment thereof to permit adjustment of said co-operating stop member to said preselected position by rotation on said threaded member while locking said co-operating stop member against movement due to relative rotation between said first stop member and said threaded member.

6. A control mechanism comprising, a rotatable shaft to be coupled to a controlled element for exerting thereon a control effect determined by the rotational displacement of said shaft with respect to a reference position, means for angularly displacing said shaft with respect to said reference position, a first stop member, a threaded member having an arcuate configuration, means for supporting said members for relative rotation therebetween in response to rotation of said shaft, a plurality of co-operating stop members individually adjustably supported by said threaded member in a preselected position and individually effective to register with said first stop member to arrest said shaft in one of a corresponding plurality of preselected control positions, and a locking device for said co-operating stop members having a resilient portion disposed in such relation to said threaded member as yieldably to engage each of said co-operating stop members in any position of adjustment thereof to permit adjustment of said co-operating stop members to said preselected positions by rotation on said threaded member while locking said co-operating stop members against movement due to relative rotation between said first stop member and said threaded member.

7. A control mechanism comprising, a rotatable shaft to be coupled to a controlled element for exerting thereon a control effect determined by the rotational displacement of said shaft with respect to a reference position, means for angularly displacing said shaft with respect to said reference position, a first stop member including a detent portion, a threaded member having an arcuate configuration, means for supporting said members for relative rotation therebetween in response to rotation of said shaft, at least one co-operating stop member adjustably supported by said threaded member in a preselected position to register with said detent portion of said first stop member and arrest said shaft in a corresponding preselected control position, and a locking device for said co-operating stop member having a resilient portion disposed in such relation to said threaded member as yieldably to engage said co-operating stop member in any position of adjustment thereof to permit adjustment of said co-operating stop member to said preselected position by rotation on said threaded member while locking said co-operating stop member against movement due to relative rotation between said first stop member and said threaded member.

8. A control mechanism comprising, a rotatable

shaft to be coupled to a controlled element for exerting thereon a control effect determined by the rotational displacement of said shaft with respect to a reference position, means for angularly displacing said shaft with respect to said reference position, a first stop member, a threaded member having an arcuate configuration, means for supporting said members for relative rotation therebetween in response to rotation of said shaft, at least one co-operating stop member adjustably supported by said threaded member in a preselected position to register with said first stop member and arrest said shaft in a corresponding preselected control position, and a locking device for said co-operating stop member including a resilient portion having substantially the same configuration as and disposed in such relation to said threaded member as yieldably to engage said co-operating stop member in any position of adjustment thereof to permit adjustment of said co-operating stop member to said preselected position by rotation on said threaded member while locking said co-operating stop member against movement due to relative rotation between said first stop member and said threaded member.

9. A control mechanism comprising, a rotatable shaft to be coupled to a controlled element for exerting thereon a control effect determined by the rotational displacement of said shaft with respect to a reference position, means for angularly displacing said shaft with respect to said reference position, a first stop member, a threaded member having an arcuate configuration, means for supporting said members for relative rotation therebetween in response to rotation of said shaft, at least one co-operating stop member adjustably supported by said threaded member in a preselected position to register with said first stop member and arrest said shaft in a corresponding preselected control position, and a circular locking device for said co-operating stop member arranged in substantially coaxial alignment with said threaded member and having a resilient portion for yieldably engaging said co-operating stop member in any position of adjustment thereof to permit adjustment of said co-operating stop member to said preselected position by rotation on said threaded member while locking said co-operating stop member against movement due to relative rotation between said first stop member and said threaded member.

10. A control mechanism comprising, a rotatable shaft to be coupled to a controlled element for exerting thereon a control effect determined by the rotational displacement of said shaft with respect to a reference position, means for angularly displacing said shaft with respect to said reference position, a first stop member, a threaded member having an arcuate configuration, means for supporting said members for relative rotation therebetween in response to rotation of said shaft, at least one co-operating stop member adjustably supported by said threaded member in a preselected position to register with said first stop member and arrest said shaft in a corresponding preselected control position, and a locking device for said co-operating stop member secured to said threaded member and having a resilient portion disposed in such relation to said threaded member as yieldably to engage said co-operating stop member in any position of adjustment thereof to permit adjustment of said co-operating stop member to said preselected position by rotation on said threaded member while locking said co-

operating stop member against movement due to relative rotation between said first stop member and said threaded member.

11. A control mechanism comprising, a rotatable shaft to be coupled to a controlled element for exerting thereon a control effect determined by the rotational displacement of said shaft with respect to a reference position, means for angularly displacing said shaft with respect to said reference position, means for limiting the maximum angular displacement of said shaft to a predetermined value, a first stop member, a threaded member having an arcuate configuration, means for supporting said members for relative rotation therebetween in response to rotation of said shaft, at least one co-operating stop member adjustably supported by said threaded member in a preselected position to register with said first stop member and arrest said shaft in a corresponding preselected control position, and a locking device for said co-operating stop member having a resilient portion disposed in such relation to said threaded member as yieldably to engage said co-operating stop member in any position of adjustment thereof to permit adjustment of said co-operating stop member to said preselected position by rotation on said threaded member while locking said co-operating stop member against movement due to relative rotation between said first stop member and said threaded member.

12. A control mechanism comprising, a rotatable shaft for exerting on a controlled element a control effect determined by the rotational displacement of said shaft with respect to a reference position, means for angularly displacing said shaft with respect to said reference position, cam means secured to said shaft and effective to couple said shaft to said controlled element, a first stop member, a threaded member having an arcuate configuration, means for supporting said members for relative rotation therebetween in response to rotation of said shaft, at least one co-operating stop member adjustably supported by said threaded member in a preselected position to register with said first stop member and arrest said shaft in a corresponding preselected control position, and a locking device for said co-operating stop member having a resilient portion disposed in such relation to said threaded member as yieldably to engage said co-operating stop member in any position of adjustment thereof to permit adjustment of said co-operating stop member to said preselected position by rotation on said threaded member while locking said co-operating stop member against movement due to relative rotation between said first stop member and said threaded member.

13. A control mechanism comprising, a rotatable shaft for exerting on a controlled element a control effect determined by the rotational displacement of said shaft with respect to a reference position, means for angularly displacing said shaft with respect to said reference position, cam means secured to said shaft and effective to couple said shaft to said controlled element, means for biasing said controlled element into engagement with said cam means, a first stop member, a threaded member having an arcuate configuration, means for supporting said members for relative rotation therebetween in response to rotation of said shaft, at least one co-operating stop member adjustably supported by said threaded member in a preselected position to register with said first stop member and arrest said shaft in a corresponding preselected control position, and a locking device for said co-operating stop member having a resilient portion disposed in such relation to said threaded member as yieldably to engage said co-operating stop member in any position of adjustment thereof to permit adjustment of said co-operating stop member to said preselected position by rotation on said threaded member while locking said co-operating stop member against movement due to relative rotation between said first stop member and said threaded member.
14. A control mechanism comprising, a rotatable shaft for exerting on a controlled element a control effect determined by the rotational displacement of said shaft with respect to a reference position, means for angularly displacing said shaft with respect to said reference position, cam means arranged in coaxial alignment with and coupling said shaft and said controlled element, a first stop member, a threaded member having an arcuate configuration, means for supporting said members for relative rotation therebetween in response to rotation of said shaft, at least one co-operating stop member adjustably supported by said threaded member in a preselected position to register with said first stop member and arrest said shaft in a corresponding preselected control position, and a locking device for said co-operating stop member having a resilient portion disposed in such relation to said threaded member as yieldably to engage said co-operating stop member in any position of adjustment thereof to permit adjustment of said co-operating stop member to said preselected position by rotation on said threaded member while locking said co-operating stop member against movement due to relative rotation between said first stop member and said threaded member.

WILLIAM M. HURST.
